UNITED STATES PATENT OFFICE.

IRA B. WHITE, OF FORT WORTH, TEXAS.

GRAIN-BAG HOLDER.

1,388,823.

Specification of Letters Patent. Patented Aug. 23, 1921.

Application filed June 11, 1921. Serial No. 476,662.

To all whom it may concern:

Be it known that I, IRA B. WHITE, a citizen of the United States, residing at Fort Worth, in the county of Tarrant and State 5 of Texas, have invented certain new and useful Improvements in Grain-Bag Holders, of which the following is a specification, reference being had therein to the accompanying drawings.

10 This invention relates to a bag holder device, and more particularly to a bag holder device which will enable an operator to hold a bag on a chute.

15 The object of the invention is the construction of a simple device that will enable an operator to hold a bag securely at one side of a chute and which holder will quickly release the bag at the will of the operator.

20 With the foregoing and other objects in view, my invention comprises certain novel combinations, constructions and arrangements of parts as will be hereinafter described, illustrated in the accompanying drawings, and more particularly pointed out 25 in the appended claims.

In the drawings:

Figure 1 is a view, in side elevation, of a device constructed in accordance with the present invention.

30 Fig. 2 is a fragmentary, front view of the device.

Fig. 3 is a top, plan view of the device.

Fig. 4 is a rear view, in elevation of the device.

35 Referring to the drawings by numerals, 1 designates the chute, preferably of a grain handling design, and to the front of the chute is secured bracket 2, which is provided with a stub shaft 3 (Fig. 2). On the stub 40 shaft 3 is journaled the substantially L-shaped or angle handle 4, which handle 4 is provided with a grip 5; the inner end 6 of the handle 4 is bifurcated, as at 7, and pivotally mounted within the bifurcation 7, on bolt 8, is the inner end of adjustable rod or link 9; the outer end 10 of rod 9 is threaded, and extends through the inner end 45 of yoke 11, with lock nuts 12, on the threaded portion 10 of rod 9 and bearing against opposite faces of yoke 11, Fig. 3. By adjusting the nuts 12 on rod 9, said rod can be adjusted on yoke 11 for taking up any slack or wear occurring upon the device.

50 The yoke 11 straddles, at its outer end, the primary link 13. A bolt 14 extends through

the outer end of yoke 11 and the upper end of link 13, pivotally connecting the link and yoke together.

Similarly constructed brackets 15 are fastened to the sides of chute 1, and supported 60 by the outer ends of brackets 15 is a shaft or rod 16. An auxiliary link 17 is mounted, at its upper end, upon one end of rod 16, against the outer side of bracket 15, and the primary link 13 is pivotally mounted on the 65 other end of rod 16, contiguous to the outer face of bracket 15. Rod 18 extends through the lower ends of links 13 and 17, and this rod is provided with a rubber sleeve or covering 19, which will permit the efficient holding 70 of the sack 20 against the side of the chute 1, as clearly shown in Fig. 1.

It is to be understood that my device is provided for the purpose of holding bags on a spout or chute without the use of hooks or 75 any other means, except as above described, and it permits the free use of one hand as soon as the holder is thrown into position. The device can be made in any size or shape 80 to fit any form of chute or spout, whether square or round.

By means of the adjustable link 9, the operator is enabled, when the rubber-covered pipe or rod 18 wears, to obtain an adjustment through link 9 and yoke 11 to take up 85 the slack and crush or hold securely the bag 20 in position.

The bag 20 goes on the spout or chute between the rubber-covered pipe or rod (Fig. 1) and the rear side of the chute when the 90 operator throws the lever upward; the hinge between the adjusting link straightens, throwing the rubber covered rod snugly against the sack and holding it against the rear side of the chute (Fig. 1); the hinge 95 passing the center slightly locking it in position.

When the bag is filled, the operator simply pulls the lever forward, releasing the bag, and it comes off without any trouble. It is 100 impossible for the bag to be removed when the lever is thrown up and the hinge passes the center.

While I have described the preferred embodiment of my invention, and have illustrated the same in the accompanying drawings, certain minor changes or alterations may appear to one skilled in the art to which this invention relates, during the extensive manufacture of the same and I, there- 110

fore, reserve the right to make such alterations or changes as shall fairly fall within the scope of the appended claims.

What I claim is:

- 5 1. In a device of the class described, the combination with a chute, of a pair of horizontal brackets fastened at their inner ends to the sides of the chute, a rod extending through the outer ends of said brackets, 10 links pivotally mounted on said rod, another rod mounted upon said links, and manually operated means connected to one of said links for moving the links and the rod supported thereby with respect to the 15 chute.
2. In a device of the class described, the combination with a chute, of bag clamping means provided with a link, carried by said chute, a bracket carried by said chute, a 20 handle pivotally mounted on said bracket, a rod pivotally connected to said handle, said

rod provided with an outer threaded end, a yoke straddling said link, means pivotally connecting the yoke and link together, the threaded end of the rod extending through 25 said yoke, and lock nuts on the threaded end of the rod and engaging opposite faces of the yoke.

3. In a device of the class described, the combination with a chute, of a bracket provided with a stub shaft secured to the side of said chute, an angle handle provided with a grip and with an inner bifurcated end journaled upon said stub shaft, a rod pivotally mounted in said bifurcated end, a 30 yoke adjustably mounted upon one end of said rod, bag clamping means movably supported upon said chute, and means connecting said bag clamping means to said yoke.

In testimony whereof I hereunto affix my 40 signature.

IRA B. WHITE.
